UNITED STATES PATENT OFFICE.

EZRA T. GILLILAND, OF INDIANAPOLIS, INDIANA, ASSIGNOR TO THE
WESTERN ELECTRIC COMPANY, OF CHICAGO, ILLINOIS.

TELEPHONE APPARATUS.

SPECIFICATION forming part of Letters Patent No. 298,161, dated February 5, 1884.

Application filed May 2, 1882. (No model.)

To all whom it may concern:

Be it known that I, EZRA T. GILLILAND, of the city of Indianapolis, county of Marion, and State of Indiana, have invented certain new and useful Improvements in Telephone Apparatus, of which the following is a specification.

The principal object of my said invention is to mount a telephone in such a manner that it may be caused to make or shunt the electrical circuit by simply pressing against it, and to break or shunt said circuit automatically when the pressure is relieved. A further object is to provide a substitute for the ordinary flexible cord commonly used with telephones. The first object is accomplished by mounting the telephone on a pivoted arm, providing points or "contact-springs," between which said arm or a projection thereon shall be capable of vibrating as the telephone is pressed upon or released, and attaching a spring to said arm or said projection in such manner as to at all times maintain a contact with one of said points when not forced toward the other. The second object is accomplished by running insulated wires along said arm, and terminating the same in a sliding or spring contact, to form the telephone connections and take the place of the ordinary flexible cord. Suitable connections in the way of binding-posts and screws are provided, as is usual. In the example shown, the arm is shown pivoted so as to be adjustable radially, and the projection is a separate piece and receives the pivots on which the arm moves in its ordinary use. This is a much more convenient and desirable construction than one wherein the arm should be all in one piece, as will be understood by the following description.

I desire, however, to distinctly disclaim any arrangement wherein the gravity of the telephone or similar force causes the disconnection.

The method of making electrical connection through insulated wire attached to the arm, instead of by a flexible cord, will be readily understood from the drawings and the description hereinafter given.

Referring to the accompanying drawings, which are made a part hereof, and on which

similar letters of reference indicate similar parts, Figure 1 is a perspective view of a box containing the call-signal apparatus for a telephone, and provided with my invention; Fig. 2, a horizontal sectional view, looking downwardly from the dotted line *z z*; Fig. 3, a vertical sectional view, looking toward the rear of the box from the dotted line *y y*; Fig. 4, a sectional view, looking toward the left from the dotted lines *x x*; Fig. 5, a side elevation of so much of the apparatus as is necessary to show my invention; Fig. 6, a plan of the electrical connections simply, and Fig. 7 a similar view to Fig. 6 of another or alternative arrangement.

In said drawings, the portions marked A represent the box; B, a bearing-plate attached to the side thereof; C, a T-shaped device pivoted to said bearing-plate; D, a spring attached thereto; E, a telephone-arm attached to said device; F, a spring-washer interposed between said device and said arm; G, the telephone; H, a connection between one of the binding-posts of the telephone and an insulated screw or pin passing through the arm E; I, a connection between the other binding-post of the telephone and a similar screw or pin, also passing through said arm; J K, said screws or pins; M² O², springs against which said screws rest; L, the main or line wire of the telephone; M, the switch-wire running to the telephone; N, the switch-wire running to the call-signal apparatus; O, the telephone ground-wire; P, the call-signal apparatus ground-wire; Q R, the transmitter-battery wires, and S the transmitter-battery. The box A is the ordinary box containing a magneto-generator and other call-signal apparatus, of any usual or approved form, which is or may be used in connection with a telephone, the magneto being the form of apparatus with which I prefer to use my invention, although it is applicable to others. The bearing-plate B is secured rigidly to the box A, and has two arms, *b b*, to contain the pivots *b' b'*, on which the device C is pivoted. These pivots are preferably in the form of pointed screws, as shown, so that the bearings may be readily and accurately adjusted. Said pivots should be secured, when adjusted, by set-screws or set-nuts, the former being shown.

The device C consists of a plate forming the head of the T, which should correspond nearly in size with the face of the rear portion of the telephone-arm, and an arm projecting through 5 into the box, which is preferably arrow-headed, and is adapted to vibrate between the contact-springs N' and M' Q' R'. The arrow-head-shaped portion is preferably of considerable width, so as to come in contact at once with 10 these contact-springs M' Q' R', as is most plainly shown in Fig. 4. The spring D is secured to the arm of the device C and to the back side of the box, and holds one point of the arrow-head-shaped part away from the 15 contact-springs M' Q' R', and preferably against the contact-spring N', except when forced in the other direction. It is also a desirable means of connecting the main line L with the device C. The telephone-arm E is secured to 20 the device C by the screw e, or in some other similar manner. It should be screwed tightly enough against said device to cause it to remain in the position in which it is placed until the position is forcibly changed. It carries 25 the telephone, in the manner illustrated, securely and in convenient position. The spring-washer F is used for the purpose of aiding in holding the telephone-arm in place. The telephone G is the ordinary hand-telephone 30 in common use. Any other receiving-telephone is, however, equally capable of use with my invention. It is usually secured to the arm E by the clamp-plate E' and screws e' e'. The connection H is preferably a piece 35 of wire so covered as to be insulated from anything with which it may come in contact between its two points of connection, which connects the binding-post g of the telephone with a screw, J, or other similar or equivalent 40 device. The connection I is a piece of wire similar to the wire H, and connects the binding-post g' of the telephone to the screw K. The screw J passes through the rear end of the arm E and against the spring M'. It is 45 electrically separated from the arm by the piece of insulating material J'. The wire H is preferably clamped between a nut, j', on this screw and a washer thereon. The spring M' is secured to the outside of the box A, and 50 extends down under the spring J, as shown. It will yield sufficiently to permit the arm to be pressed inwardly and allow it to move outwardly during the ordinary use of this device, and is wide enough so that the point of 55 the screw J will remain in contact therewith, notwithstanding any ordinary movement of the arm on its pivot. This spring is usually connected to the telephone-wire M. The screw K and spring O' are similarly constructed, 60 and perform substantially the same functions as the screw J and spring M'. The spring O' is preferably connected to the ground-wire O. The main wire L is connected to the device C in some suitable manner. A very 65 simple and convenient means of making this connection is through the spring D.

Referring now to Fig. 6, it will be seen that

when the apparatus is in its normal position, with the arrow-head-shaped part resting against the contact-spring N', the current 70 passes through the call-signal apparatus and to the ground, leaving the telephone entirely cut out. When, however, the switch is turned, with the arrow-head-shaped part resting against the contact-spring M', the current 75 passes through the telephone, and the latter is in condition for use. The wire M is the wire by which the telephone is connected to the line. In the arrangement shown (most 80 plainly in Fig. 2) the connection H, spring M', wire M, (see Fig. 4,) and contact-spring M' are each, electrically considered, a part of this wire or line, said contact-spring being the termination when the apparatus is in normal position. The wire N is a short-circuiting or 85 cut-out wire, by which the telephone is cut out from the main circuit and the call-signal apparatus thrown in. It terminates in the contact-spring N', to which it is connected by a binding-screw or otherwise. It is usually so 90 arranged in telephone apparatus as to turn the circuit from the telephone to the call-signal apparatus when brought in contact with the switch. The wires O and P run from the telephone and call-signal apparatus, respectively, to the ground. The wires Q and R and the contact-springs Q' R', in which they terminate, constitute means whereby this invention 95 operates to connect the transmitter-battery circuit at the same time the telephone is 100 put in use, and correspond closely to similar wires or strips used in apparatus wherein the gravity-switch is employed.

Instead of the arrangement heretofore described, that illustrated by Fig. 7 may be used, 105 whereby instead of cutting out the instruments they are simply shunted or short-circuited. Another modification of this device would be substantially reversing the course of the current, as shown in said Fig. 7—i. e., using what 110 is therein shown as the ground-wire for the line-wire, and what is shown as the line-wire for the ground-wire. In this latter arrangement a modification in the mechanical part of the invention could also be accomplished. Instead of running the connection H to the screw 115 J, it could in this last-described case be connected to the body of the arm E, thus making said arm and the device C serve as the greater portion of one side of the telephone-circuit. 120

The operation of my invention is as follows: The apparatus being in the position shown, the spring D holds the device C away from the contact-spring M', thus keeping the telephone G cut out or short-circuited, which is 125 or should be the normal condition of the telephone in properly-constructed apparatus, except when in use. It also in this condition keeps the transmitter-battery circuit open. When it is desired to use the telephone, the 130 user simply presses his ear against the mouth thereof, and the pressure, being communicated to the device C through the arm E, overcomes the force of the spring D and causes the arrow-
